CLOTHES CHUTE

Joseph E. Spearman, East Detroit, Mich.

Application November 5, 1951, Serial No. 254,816

1 Claim. (Cl. 193—34)

1 This invention relates to new and useful improvements and structural refinements in clothes chutes which are commonly employed in homes for the purpose of conveying soiled clothes by gravity from one floor level to another.

It frequently occurs that the clothes become lodged in the chute so as to obstruct the same, whereupon the housewife must necessarily ascend to the upper floor level and endeavor to release the obstruction by manipulating a stick, or the like, in the chute. The instant invention seeks to avoid this disadvantage by the provision of means for expeditiously and conveniently relieving any obstruction in the clothes chute without the necessity of ascending to an upper floor level, this being achieved by the provision of what may be called a clothes dislodging member which is carried by a cable in the clothes chute and may be caused to travel upwardly and downwardly therein, so as to free the same of any obstruction.

Some of the advantages of the invention lie in its simplicity of construction, in its efficient and dependable operation, and in its adaptability to installation in clothes chutes of different sizes and types.

With the above more important objects and features in view, and such other objects and features as may become apparent as this specification proceeds, the invention consists essentially of the arrangement and construction of parts as illustrated in the accompanying drawings, in which:

Figure 1 is a vertical sectional view of a clothes chute, showing the invention installed therein;

Figure 2 is a sectional detail on an enlarged scale, taken substantially on the plane of the line 2—2 in Figure 1;

Figure 3 is a sectional detail, taken substantially in the plane of the line 3—3 in Figure 2; and

Figure 4 is a perspective view of the dislodging member used in the invention.

Like characters of reference are employed to designate like parts in the specification and throughout the several views.

Referring now to the accompanying drawings in detail, the general reference character 10 designates a vertically elongated clothes chute which is installed in a suitable duct 12 extending from an upper floor level 14 to a lower floor level 16, the chute 10 having an inlet opening 18 and an outlet opening 20 at the respective upper and lower ends thereof, as will be clearly apparent.

Preferably, the upper end wall 22 of the chute is disposed somewhat above the upper edge of the

inlet opening 18, and the invention contemplates the provision of a slidably telescoped supporting rod 24 which is provided with angulated end portions 26 whereby it may be suitably secured by fastening elements 28 in the upper end of the chute 10, substantially above the inlet opening 18.

An inverted U-shaped yoke 30 is mounted on an intermediate portion of the supporting rod 24 and carries a bolt 32 on which is positioned a spacer sleeve 34, the bolt 32 also having a nut 36 whereby the yoke 30 may be firmly clamped in position on the rod 24.

A pulley 38 is freely rotatable on the sleeve 34 and a flexible cable 40 passes around this pulley and has one end thereof extended through an aperture 42 at the center of a horizontally elongated dislodging member or plate 44. That end of the cable is provided with a knot 46 to prevent it from being withdrawn through the aperture 42, it being observed that the cable 40 extends upwardly from the plate 44, around the pulley 38 and then downwardly so that an intermediate portion of the cable passes slidably through an opening 48 in the plate 44. The cable then passes downwardly to the lower end of the clothes chute 10 and then upwardly, the other end thereof being tied as at 50 to a rope 52 which is anchored at the opposite ends thereof in a pair of apertures 54 provided in the end portions of the plate 44.

When the invention is not in use, the plate 44 is disposed adjacent the pulley 38, it being understood that under such circumstances clothes may be inserted in the chute through the opening 18 for gravitation to the lower floor level 16, but if obstruction should occur in the chute, a person removing the clothes through the opening 20 at the lower floor level 16 may simply actuate the cable 40 so as to cause the plate 44 to travel downwardly through the chute, to relieve or dislodge the obstruction. Thereupon the plate 44 may be returned to the upper end of the chute, it being understood that the plate 44 is sufficiently light and the cable 40 is sufficiently heavy so that the inertia of the cable normally prevents the plate 44 from descending by the action of gravity.

A suitable stop 56, such as a knot, or the like, may be provided on an intermediate portion of the cable 40 so as to come in contact with the pulley 38 when the plate 44 is at the lower end of the chute, the stop 56, of course, being of such size as to pass freely through the opening 48 in the plate 44.

It is believed that the advantages and use of the invention will be readily understood from the foregoing disclosure and accordingly, fur-

ther description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In combination, a clothes chute having a closed upper end and a side inlet spaced below and contiguous said upper end, a telescopically adjustable rod fixed transversely in said upper end 15 above said inlet a pulley in said upper end above said inlet suspended from said rod, a horizontal

clothes dislodging solid plate in said chute and a cable looped around said pulley and suspended thereby with opposite ends attached to said plate and operative on said pulley to lift the dislodging plate into the upper end of the chute above said inlet into and out of the way position, said plate being smaller than said chute to obviate frictional engagement of the plate with the chute and binding of said plate in the chute.
